GOLF PRACTICE MIRROR

Edmund Bruce Blythe, Jr., 429 Commonwealth Bldg.,
Louisville, Ky.

Filed Apr. 14, 1961, Ser. No. 64,730

Term of patent 3½ years

(Cl. D34—5)

Fig. 1.

Fig. 2.

Fig. 3.

I claim:

The ornamental design for a golf practice mirror, as shown and described.
